CALKED SOLE

Filed Nov. 24, 1928

UNITED STATES PATENT OFFICE

HORATIO A. SMITH, OF EDMONDS, WASHINGTON

CALKED SOLE

Application filed November 24, 1928. Serial No. 321,550.

This invention relates to improvements in calked soles and aims primarily to provide a calked sole that is capable of ready adjustment to various sizes and types of boots or 5 shoes, that is especially designed for rapid attachment thereto and similar removal therefrom, that is particularly adaptable for use by fishermen, hunters, loggers, mountaineers, shinglers, and the like, and that will not be 10 come clogged while in use.

Contemplated by the present invention is a self-cleaning flexible calked sole embodying a calked sole section, a shank section hingedly connected to said sole section, a heel section 15 longitudinally adjustable upon said shank section, laterally adjustable means for securing the sole section to the shoe or boot of the wearer, means for securing the heel section to such shoe or boot, and a series of integral 20 calks of novel form disposed in spaced relation upon the perimeters of the sole and heel sections, all of which are important objects of the invention and are to be correlated in the broad aim of enhancing the efficiency of 25 the device for general use.

The above, and additional objects which will hereinafter be more specifically treated, are attained by such means as are shown in the accompanying drawings, described in the 30 following specification and then more clearly pointed out in the claims, which are appended hereto, and form a part of this application.

With reference to the drawings in which 35 there is illustrated one embodiment of the invention, and throughout the several views of which like characters of reference designate similar parts.

Figure 1 is an elevation of a calked sole 40 comprehended by the present invention, as it would appear when attached and adjustably secured upon a shoe, which latter is shown in dot and dash lines therein.

Fig. 2 is a top plan view thereof, certain 45 parts being omitted and certain other parts being shown in section for clarity of illustration.

Fig. 3 is an elevation of the rear end of the 50 same.

Fig. 4 is an elevation of the front end thereof.

Figs. 5 and 6 are vertical transverse sections taken through 5-5 and 6-6, respectively, of Fig. 2. 55

Fig. 7 is a fragmentary horizontal section taken through 7-7 of Fig. 5.

Fig. 8 is a similar section taken through 8-8 of Fig. 6.

Fig. 9 is a fragmentary longitudinal section taken through 9-9 of Fig. 2. 60

Fig. 10 is an enlarged fragmentary elevation of the type of calk employed with the sole.

Fig. 11 is a vertical transverse section 65 thereof taken through 11-11 of Fig. 10, and

Fig. 12 is a horizontal section of the same taken through 12-12 of Fig. 10.

Beginning the more detailed description by reference to the accompanying drawings, 70 the numeral 15 designates a shoe, of any well known type, to which is adjustably secured against longitudinal and lateral dislodgement thereon a flexible calked sole 16 fabricated in accordance with the present invention and comprising a sole or forward section 17, to the rear end of which is hingedly connected, as at 18, a central or intermediate section 19 having a relatively narrow rearwardly extending integral tongue 20, to which is adjustably secured a forwardly extending integral shank 21 of a downwardly offset heel or rear section 22 having the material at its rear end bent upwardly to form a heel retaining portion 23. 75

The sections 17, 19 and 22 are fabricated from sheet steel, or the like, and disposed in spaced relation upon the perimeter of the sole section 17 and similarly upon the perimeter of the heel section 22 is a series of triangular corrugated calks 24, which are struck from the material of said sections and bent downwardly from the edges thereof substantially at right angles thereto, the apexes of said triangular calks constituting sharpened 90 gripping points. During the die stamping or forming of the calks 24, the same are flexed to provide corrugations 25 therein, which latter are formed in parallel relation to the axes of the calks, as shown more clearly in 95 100

Figs. 10 and 12, this for the purpose of reinforcing such calks and for providing a particularly rugged type of calk capable of considerable resistance against distortion.

5 Struck from the sole section 17 and the intermediate section 19 is a central row of transversely disposed calks 26, which are also of triangular and corrugated formation. By forming the calks 24 upon the respective 10 perimeters of the sections 17 and 22 in the manner herein shown and described, it will be observed that such calks are longitudinally disposed in substantially parallel relation to the axes of their correlated sections, thus 15 permitting of any bending action or stress upon the calks being applied longitudinally thereof and not transversely, whereby any tendency of such calks to bend during rough usage is effectively minimized, for the reason 20 that the load is imposed thereon in an edge-wise or sidewise direction, and due to the reinforcing action of the corrugations 25 said calks will withstand considerable stress without fracture. It will also be noted by referring 25 to the accompanying drawings, that the arrangement of the calks 24 and 26 effectually prevent lodgement of any foreign matter or dirt therebetween, and that with such arrangement the present calked sole is self-cleaning inasmuch as there is sufficient open 30 space and flat surfaces between the rows of calks, so that any foreign matter or dirt is ejected and cannot become clogged between the calks.

35 Detachably secured, as by a screw 27, to the forward end of the sole section 17 is a toe cap or protective member 28, adapted to normally abut the toe of the shoe 15, when the calked sole is in use, whereat such member 40 functions to effectually prevent débris from finding lodgement between the forward end of the calked sole and the sole of the shoe.

The sole section 17 is provided substantially midway the length thereof with a laterally disposed downwardly offset channel or guide 45 29, the bottom wall of said channel adjacent its ends and at each side thereof having lugs 30 struck therefrom, which latter are retained in the plane of the sole section 17.

50 Slidably interposed between the channel 29 and the lugs 30 are angularly formed sole retaining members or keepers 31, the upwardly bent outer ends of which are adapted to normally abut the sides of the sole of the shoe 15, to thereby prevent sidewise or lateral dislodgement of the sole section 17 thereon. Formed and provided within each inner terminal portion of the sole retaining members 31 are slots 32 having a series of opposed notches 33 cut in the sides thereof. Selectively insertible within the notches 33 and threadedly engaged within the bottom wall of the channel 29 are screws 34, which latter serve and function to secure the sole retaining members 31 in predetermined laterally ad-

justed positions, within and relative to the sole section 17, which positions are determined by and regulated in accordance with the width of the shoe to which the calked sole is applied. It will be apparent and obvious from the foregoing and by reference to the drawings that vertical dislodgement or displacement of the sole retaining members 31 from the channel 29 is effectually prevented by the lugs 30, which function to maintain such members within said channel. The sole section 17 is adjustably secured to the vamp portion of the shoe 15 by a sectional strap 35 having its outer terminals riveted to the outer ends of the sole retaining members 31 and having its opposing inner terminals adjustably connected by a frictional buckle 36.

The tongue 20 of the intermediate section 19 is provided with a longitudinally disposed central slot 37 having a series of opposed notches 38 cut in the sides thereof, said tongue being also slidably interposed for longitudinal adjustment between the shank 21 of the heel section 22 and a transversely disposed strip 39 of relatively light flexible material, the terminal portions of which are flexed downwardly to pass through longitudinally disposed slots 40 formed within the edge portions of the shank 21 and are return bent thereat to provide upwardly extending apertured terminals 41. To secure the tongue 20 in a predetermined longitudinally adjusted position upon the shank 21, a screw 42 is provided, which extends through the strip 39 and the selected notches 38 of the tongue 20 and at its lower end is threadedly engaged within the shank 21. Straps 42 provided with elongated ring members 43 at their forward looped ends have their forward terminal portions slidably disposed within the apertured terminals 41 and also within the members 43 and at their rear looped ends are engaged within angularly disposed slots 44 formed within the heel retaining portion 23. A sectional strap 45 having its outer looped ends engaged within the ring members 43 and having its opposing inner terminals adjustably connected by a frictional buckle 46 is provided to adjustably secure the shank 21 and heel section 22 to the heel or rear portion of the shoe 15. It will be noted by referring to the drawings, that by employing the type of straps herein shown and described, that such straps readily conform and automatically adjust themselves to the contour of the heel or rear portion of the shoe 15 irrespective of the size or type thereof, while also furnishing a rapid and efficient means for adjustably securing the heel section 22 to the shoe 15.

In attaching the flexible calked sole 16 to the shoe 15, the tongue 20 is longitudinally adjusted upon the shank 21 to accommodate such shoe, the retaining members 31 are then

laterally adjusted for the same reason, whereupon the calked sole is ready for attaching to the shoe, which latter is effected by adjustably securing the straps 35 and 45 with their respective buckles 36 and 46 in an obvious manner.

Manifestly, therefore, the calked sole of the present invention is extremely simple, durable and economical in construction, is efficient and reliable in use, possesses the requisite flexibility to assure of ease and comfort in walking, will not cramp the shoe or foot of the wearer, will effectually prevent slipping upon icy or other slippery surfaces, and will not mar or injure the shoes or boots when positioned thereon.

While I have herein shown and described my invention with sufficient detail to enable those skilled in the art to understand the mode of construction and the principles involved, it is to be understood that there is no intentional limitation herein to the specific form and precise details of construction of the invention shown and described except as expressly defined by the appended claims, and that various modifications of said construction may be resorted to without departing from the invention, or the benefits derivable therefrom. I also desire to have it understood that certain features of the invention herein shown and described may be employed in other combinations than those herein shown.

Having thus fully described my invention, what I claim as new and desire to secure by Letters Patent, is:

1. The combination in a calked sole for a shoe, of a triangular corrugated calk struck from the material of said sole and bent downwardly at right angles thereto.

2. The combination in a calked sole for a shoe, of a triangular calk struck from the material of said sole and bent downwardly at right angles thereto, said calk having a series of corrugations formed thereon substantially in the direction of the length of same.

3. The combination in a calked sole for a shoe, of a triangular calk struck from the material of said sole and bent downwardly at right angles thereto, said calk having a series of corrugations formed thereon in parallel relation to its axis.

4. The combination in a calked sole, of a heel section having a forwardly extending shank portion provided adjacent its side edges with longitudinally disposed slots, a transversely disposed strip of flexible material having apertured terminal portions flexed downwardly to pass through said slots and return bent to provide upwardly extending apertured terminals adapted to receive means for securing said heel section to the shoe.

In testimony whereof I affix my signature.

HORATIO A. SMITH.
